[57] **ABSTRACT**

An electric signaling device for battery alarm clocks having a switching device with a double contact and a common contact element and two separate contact elements cooperating with the common contact element. The separate contact elements are arranged in stepped relation and the contacts being operable by the clock movement.

ELECTRIC SIGNALING DEVICE FOR ALARM CLOCKS

This invention relates to an electric signaling device for alarm clocks, particularly for battery operated alarm clocks, with a switching device to be operated by the movement of the clock, and is a divisional application of application Ser. No. 672,819, filed Oct. 4, 1967 now U.S. Pat. No. 3,534,543.

The invention provides an electric signaling arrangement for alarm clocks, which, while being of a simple structure, will guarantee a safe and sure method of operation and which, after operation of a signal transmitter, will be ready for operation again within a short period of time. According to the invention, the switching arrangement, operated by the movement of the clock, has been developed as a double contact with one common contact element and two separate contact elements cooperating with said first element, and in that the separate contact elements have been arranged in staggered relationship between the separated contact elements and the contact elements in common in relation to the relative movement produced by the movement of the clock so as to come in contact with the common contact element one after the other. Preferably, the contact path which is closed first is connected with a transmitter of a warning signal and the second contact path is connected with a transmitter of a primary signal. At the same time, the transmitter of the warning signal can be of any desired type. Preferably, however, one will use an electronic transmitter for the warning signal, resulting in a simple structure with the double contact in the case of a comprehensive method of operation.

Further objects will be apparent from the following description when considered in connection with the accompanying drawings in which:

FIG. 1 is a cross section of a portion of an alarm clock taken on lines I—I of FIGS. 2 and 3;

FIG. 2 is a sectional view taken on line II—II of FIG. 1;

FIG. 3 is a sectional view taken on line III—III of FIG. 1;

FIG. 4 is a sectional view of a detail taken on line IV—IV of FIG. 3;

FIG. 5 is a cross section of a modified construction of a single rotary contact taken on lines V—V of FIGS. 6 and 7;

FIG. 6 is a sectional view taken on line VI—VI of FIG. 5;

FIG. 7 is a sectional view taken on line VII—VII of FIG. 5;

FIG. 8 is a sectional view of a detail taken on line VIII—VIII of FIG. 7;

FIGS. 9a to 13c are diagrammatic view illustrating the contacts in different operating positions;

FIG. 14 is a cross section of a further modified construction of a portion of an alarm clock taken on line XIV—XIV of FIG. 15;

FIG. 15 is a sectional view taken on line XV—XV of FIG. 14;

FIG. 16 is a cross section of an adjusting wheel;

FIG. 17 illustrates an application of the apparatus;

FIG. 18 is a wiring diagram of an electronic multivibrator circuit;

FIGS. 19 to 21 are wiring diagrams showing various electronic multivibrator circuits.

The plate member 10 in FIGS. 1 to 4, consisting of an insulating material, supports the dial 12. 11 designates a second plate member or frame. In plates 10 and 11, a minute shaft 13, carrying the hand 14, has been mounted. The hour sleeve or tube 15 carrying the hand 16 is mounted on the minute shaft 13, the hour sleeve in turn being encompassed by a bushing 20 carrying the hand 21 for the setting of the alarm. This bushing 20 has been mounted rotatably and in frictional engagement with the plate member 10. On the side facing away from the dial 12 there is provided the adjusting wheel 17 for the alarm, which is adjustable with the aid of a pinion 18 on a shaft 19.

On the side of the plate member 10 made of nonconductive material and facing away from the dial 12, there is provided a contact ring 22 made of electrically conductive material, with which a line or wire 23 has been connected.

The adjusting wheel 17 of the alarm has been provided with an outside or peripheral rim 17b and has in its center part a

cavity, in which a contact spring 24 has been fastened with the aid of rivets 25. In the adjusting wheel 17, a perforation 17a has been provided, which is within the area of the contact ring 22. The contact point of the spring contact 24 protrudes through the perforation 17a and slides on the contact ring 22. The rear end 24b of the contact spring 24 has been bent at a right angle and this end penetrates through a slot in the fortified edge 17b of the adjusting wheel 17 of the alarm to form a contact strip, which can be brought into electric contact with a contact sliding on the edge 17b.

On the hour sleeve or tube 15, a wheel 26 is fastened by means of an insulating bushing 26a, which consists of the ring elements 26b and 26d, which are electrically conductive and have been separated electrically one from the other by an additional insulating bushing 26c. The contact spring lamellae 28 and 27 are connected with the two electrically conductive ring elements 26b and 26d, which lamellae rest or contact on the edge 17b of the adjusting wheel 17 of the alarm. The two contacts 27 and 28 have been staggered in relation to one another somewhat in the direction of travel of the wheel 26, so that they will not come in contact with the contact strip 24b simultaneously. The method of operation will be explained hereinafter with reference to FIGS. 9 to 13.

The slipsprings 29 and 30, on which two contact springs 31 and 32 slide and which are connected to wires 33 and 34 arranged on the outside periphery of the wheel 26, are associated with the contacts 27 and 28 respectively.

It is also possible to use, instead of the contact ring 22 in a plate member 10 of a nonconductive material, a plate of an electrically conductive material on which the contact 24a will slide directly. However, in that case the movement of the clock will be under tension.

FIGS. 5 to 8 show a modified design by way of example, with only one rotating contact. The same parts in this case have been given the same reference numbers for corresponding parts. In this case, two concentrically located contact rings 40 and 41 are provided in the plate 10, made of nonconductive material, and are provided with electrical connectors (not shown). The adjusting wheel 46 of the alarm has been arranged on the bushing 20, which in this case has been developed with a protruding edge 46c, FIG. 8. Perforations 46a and 46b have been provided in two annular grooves of the adjusting wheel 46 of the alarm, through which spring contacts 47 and 48 project. These two contact springs 47 and 48 are in electrically conductive contact with the contact rings 40 and 41.

The ends 47b and 48b of the contact springs 47 and 48, respectively, are bent at right angles and penetrate through the projecting edge 46c. Ends 47b and 48b are separated by a small distance as shown in FIG. 7.

A disk 49b is mounted on the hour tube or sleeve 15, with the aid of an insulating bushing 49a, and carries a spring contact 50. This spring contact 50 glides on the protruding edge 46c of the adjusting wheel 46. The contact lamella 50 is electrically conductively connected with the electrically conductive disk 49b. A contact spring 51 slides on the periphery of the disk 49b and is provided with wire 52.

The method of operation of the structure according to FIGS. 1 to 8, given by way of example, will be explained in more detail in the following paragraphs on the basis of FIGS. 9 to 13. FIGS. 9a-13a illustrate operative positions of the two contacts; FIGS. 9b-13b illustrate contacts according to the structure of FIGS. 1 to 4; and FIGS. 9c-13c illustrate the contacts according to the structure of FIGS. 5 to 8.

FIGS. 9a-c show the position of the contacts shortly before reaching the time for sending out the alarm. Both contact paths S₁ and S₂ in this case are open.

In FIGS. 10a-c the first contact has been closed in the direction of movement of the contact, while the second contact has not reached the contact strip or the contact strips as yet. The contact path S₂ therefore is still open.

In FIGS. 11a-c both contacts are in contact with the switching strip or switching strips, that is, both contact paths S₁ and S₂ are closed.

FIGS. 12a-c show the position in which the first contact in the direction of movement, is opened. In FIG. 12b the first contact in the direction of movement has left the contact strip 24b, while the following contact 28 is still located on the contact strip 24b. In FIG. 12c the rotating contact 50 has left the first contact strip and is still only located on the second contact strip 47b. Consequently, the contact path S₁ is open, while the contact path S₂ is still closed.

FIG. 13a shows a position in which the two contact paths S₁ and S₂ are again open and thus the signaling device has been completely switched off. In FIG. 13b both contacts 27 and 28 have left contact strip 24b, and in FIG. 13 contact 50 has left both contact strips 47b and 48b.

In FIGS. 14 to 16, a third embodiment is illustrated. In this embodiment the adjusting wheel 60 is mounted to the bushing 20, and the adjusting wheel is partially in the shape of a hollow cylinder. Two contact springs 63 and 64 are mounted within the hollow cylindrical part with their respective contact ends 63b and 64b pointing approximately in the direction of the middle axis of the adjusting wheel 60. The contact springs 63 and 64 are connected by declinated flanges 63a and 64a with sliprings 61 and 62 arranged on the outside periphery of the adjusting wheel 60, on which sliprings two contact springs 69 and 70 slide, which are provided with wires 71 and 72.

A disk 65 made of insulating material is placed on the hour cylinder or sleeve 15, which rotates together with the hour hand. Disk 65 carries a slipping 66 on one of its front sides, on which slides a contact spring 67 which leads to a solid connector 68. The contact ring 66 has been provided with a projecting flange 66a, which has been bent at right angles and which is located in the base of a notch 73 in the disk 65. This notch includes an edge 65b running approximately radially and preferably being undercut, and with an edge 65a which runs approximately perpendicularly thereto. The bent flange 66a of the slipping 66 also preferably is likewise undercut. The direction of movement of the disk 65 has been indicated by an arrow. Because of the special development of the notch 73, the contact points 63b and 64b, upon reaching the edge 65b, will suddenly drop into notch 73, so that an instantaneous contact takes place with projecting flange 66a. Also, disengagement of the contact points is accomplished momentarily in a similar manner. Otherwise the method of operation is the same as in the case of the structure illustrated by way of example in FIGS. 1 to 8.

In FIG. 17 the method of operation of the device according to the invention has been shown schematically. MV is a warning signal transmitter, which may be of any desired kind. One uses preferably as a warning signal transmitter, an electric transmitter which, for practical purposes, is developed as a transistor-multivibrator. An alarm bell L, for example, has been connected to this alarm signal transmitter MV. Instead of an alarm bell, any other acoustic or an optic signal transmitter, for example, an electric bulb or lamp, can be used. S₁ and S₂ are the contact members opened and closed through the previously described contact arrangement. If the contact path S₁ is closed, then the alarm signal transmitter MV is placed into operation, as a result of which, for example, the signal transmitter L is fed by impulses. If subsequently the contact path S₂ is closed, then the alarm signal transmitter MV is shorted, so that now the signal transmitter L is fed continuously and thus it transmits a constant signal.

In FIGS. 18 to 21, various electronic multivibrator circuits are shown, which can be used, for example, as alarm signal transmitters MV in FIG. 17.

FIG. 18 shows a multivibrator circuit using complementary transistors T₁₁ and T₂₁. The subsequently added power transistor T₃₁ in this case serves to drive the load.

During the pulse pause, in this case, the two transistors T₁₁ and T₂₁ are blocked. T₁₁ will remain blocked until the condenser C will be charged by the resistances R₁₁, R₂₁ and R₃₁ to such a point that the threshold voltage of the base-emitter path of transistor T₁₁ has been reached. First of all a small base current will flow, which is fed, after having been increased by the increase of this transistor, to the transistor T₂₁ as a control

current. The transistor T₂₁ thereupon becomes conductive and the through-connection of transistor T₁₁ will be accelerated by the feedback through the resistance R₂₁ and the condenser C. Thereupon the transistors T₁₁ and T₂₁ are opened. The condenser C is then recharged by the base-emitter path of the transistor T₁₁ until it falls short of the threshold voltage of the transistor T₁₁ and the multivibrator tips back into the starting state. The method of operation of the multivibrator is started as soon as the contact path S₁ is closed. The transistor T₃₁ is switched according to the switching state of the transistor T₂₁, the signal transmitter L being switched in the collector path of said transistor T₃₁, which transmitter is thus fed by means of the current pulses created by the transistor T₃₁. The RC element from the condenser C and the resistance R₃₁ and R₂₁ determine, respectively, the duration time of the pause and the transmission time of the impulse.

If the contact member S₂ is closed, then the transistor T₃₁ is bridged and the signal transmitter L is fed directly from the source of DC current, for example, from a battery.

D is a diode connected in parallel to the signal transmitter L, for example, an alarm bell, through which diode surges occurring during the operation are supposed to be suppressed.

A multivibrator circuit is shown in FIG. 19 which uses only transistors which are of the same type conductivity. In the present case, PNP transistors have been used which, in comparison with NPN transistors, are considerably less expensive. For that reason one will have to put up with a somewhat lower degree of effectiveness, which in this case is of no particular importance.

The actual multivibrator is formed by the transistors T₁₂, T₂₂ and T₃₂. Another transistor T₄₂ has been provided here for the adaptation of power.

During the pulse pause, transistors T₁₂, T₃₂ and T₄₂ are blocked, while transistor T₂₂ is opened. Transistor T₁₂ remains blocked until condenser C has been charged by resistances R₁₂, R₂₂ and R₃₂ to the point where the threshold voltage of the base-emitter path of transistor T₁₂ has been reached. First of all a small base current, which allows the collector-emitter path of transistor T₁₂ to become conductive, will close. The transistor T₂₂ thus receives a smaller negative base-emitter voltage, as a result of which its collector-emitter path becomes less conductive and the base of transistor T₃₂ will be at a negative potential, so that the transistor T₃₂ will be turned on. The through-connection of the transistors will be accelerated by the feedback R₄₂, C. After that, the transistors T₁₂ and T₃₂ are opened, while T₂₂ is blocked. The base of the transistor T₄₂ is controlled by the opened collector-emitter path of the transistor T₃₂, so that this transistor too is opened and feeds the signal transmitter L located in its output circuit.

The condenser C is recharged by the base-emitter path of the transistor T₁₂ and by resistances R₄₂, and the opened collector-emitter path of the transistor T₃₂, until it falls below the threshold voltage of transistor T₁₂, as a result of which the transistors change their switching state and the circuit tips back into its starting state, in which the current is broken by the signal transmitter L.

In the case of modification given by way of example according to FIG. 20, the previously used adaptation of the transistor has been omitted. This is not possible without any difficulties in the case of the customary multivibrators, since, by switching on and off the signal transmitter L of an alarm bell, for example, through the interrupter contact, the impulses created are superimposed on the multivibrator impulses. In the case of the present circuit, this disadvantage does not have any disturbing effect. In this case the signal transmitter L has been switched in between the positive pole of the source of voltage and the emitter of transistor T₃₃.

Since during the pulse pause the interrupter contact of the alarm bell L is closed, the condenser C can be charged by the resistances R₁₃ and R₄₃ as well as by the winding of the alarm system. In the case of recharging via the base-emitter path of the transistor T₁₃ and the resistances R₄₃ and the opened collector-emitter path of T₃₃, it will then be unimportant if the in-

rupter contact of the alarm system L is opened or closed during the time that the bell rings.

The switching arrangement according to FIG. 21 has been further simplified in that the feedback is accomplished directly from the collector of the transistor T_{24} by the resistance R_{44} and the condenser C to the base of the transistor T_{14} and in that the alarm system L is now located within the collector branch of the transistor T_{34} . As a result thereof, the above-mentioned disadvantage of the superimposition of impulse is eliminated.

In this case too, just as in the remaining circuits, a diode D has been provided in parallel to the alarm system L, which serves for quenching the sparks and which thus prevents the occurrence of surges during the opening of the circuit containing the magnetic coil.

What is claimed is:

1. An electric switching device, comprising; first and second switch contact means, an adjusting wheel and a wheel mounted in parallel spaced relation with said adjusting wheel, a driving mechanism for rotating said wheel, said adjusting wheel and said wheel are rotatable with respect to one another, said first switch contact means are mounted on said adjusting wheel and said second switch contact means are mounted on said wheel, said first switch contact means including at least one element extending perpendicularly from said adjusting wheel and said second switch contact means including at least one spring contact member extending perpendicularly to the plane of rotation of said first and second switch contact means, said adjusting wheel including an insulated contact strip connected to said at least one element, and said at least one spring contact member engaging said insulated contact strip, said first and second switch contact elements

each having a narrow cross section so as to contact one another to provide two momentary successive contacts with the rotation of said wheel.

2. The switching device as in claim 1 wherein said second switch contact means consists of two electrically insulated contact members resiliently mounted in spaced relationship on said wheel and momentarily contacting said first switch contact means during the relative rotation of said wheel with respect to said adjusting wheel.

3. The switching device as in claim 2 wherein said wheel includes a pair of spaced sliprings, each slip ring is in electrical contact with one of said two insulated contact members, and additional spring contact means engaging said slip rings to provide an electrical connection to said spring contact members.

4. A switching device as in claim 1 wherein said first switch contact means includes two spaced members each extending perpendicularly from said adjustment wheel towards said wheel, said wheel includes an insulated contact member electrically connected to each of said spaced members, said second switch contact means includes a resilient spring contact mounted to said wheel and extending perpendicularly therefrom to engage insulated contact member, whereby said spaced members each successively contact said resilient spring contact to provide two momentary contacts during each revolution of said wheel.

5. A switching device as in claim 4 wherein said wheel includes a slipring mounted thereon and connected to said spring contact, and an additional spring contact member in engagement with said slip ring.
